UNITED STATES PATENT OFFICE.

GEORGE E. SLOAN, OF MINNEAPOLIS, MINNESOTA.

SCAFFOLD SUPPORT.

Application filed October 24, 1927. Serial No. 228,365.

This invention relates to new and useful improvements in scaffold supports and more particularly relates to such a support of the portable type and which is constructed of 5 metal.

An object of the invention is to provide an all-metal scaffold support which may be collapsed or folded into a comparatively small bundle when not in use, and, which is 10 so constructed that it may be detachably secured to a wall or upright in comparatively short time.

A further object of the invention is to provide a scaffold support comprising an arm 15 having an elongated opening at one end thereof adapted to receive a tongue provided upon one end of a leg, the other end of which is provided with a tooth or prong adapted to engage the surface of the wall 20 or upright, and the arm having a bracket secured to the opposite end thereof, wherein a plurality of slots are provided, each having an enlarged portion adapted to receive the head of a nail, and the reduced end portions of said slots being adapted to engage 25 the body of a nail, back of its head, to prevent the bracket from accidentally becoming disengaged from the wall, and at the same time permitting the bracket to be disengaged from the nail or nails to remove it 30 from the wall.

Features of the invention reside in the general construction of the support, as a whole; the provision of the key slots adapted to receive 35 ordinary nails for securing one end of the arm to a wall or upright; the connection between the arm and the leg, which permits inverting the arm; the use of the brace member having one end pivotally connected 40 to the arm and its other end adapted to be engaged with the wall to prevent swaying of the support; the means for securing the lower end of the leg to the wall surface; and, in the hook member provided at one 45 end of the arm, whereby the latter may be utilized on the surface of a roof as a supporting means for a foot rest such, for example as a two-by-four, such as is commonly used to provide a support for a workman, 50 when shingling or surfacing a roof.

Other objects of the invention will ap-

pear from the following description and accompanying drawings and will be pointed out in the annexed claims.

In the accompanying drawings there has 55 been disclosed a structure designed to carry out the various objects of the invention, but it is to be understood that the invention is not confined to the exact features shown as various changes may be made within the 60 scope of the claims which follow.

In the accompanying drawings forming part of this specification;

Figure 1 is a sectional plan view illustrating the corner of a building with my 65 improved scaffold supports secured thereto;

Figure 2 is a sectional elevation on the line 2—2 of Figure 1;

Figure 3 is a sectional elevation on the line 3—3 of Figure 1;

Figure 4 is a perspective view showing the bracket secured to the end of the arm for detachably connecting the arm to the wall;

Figure 5 is a detail view showing the connection between the outer end of the arm and 75 the leg;

Figure 6 is a plan view of Figure 5;

Figure 7 is a view showing the lower end 80 of the leg and the means provided thereon for engaging the wall or upright;

Figure 8 is a view showing the slot provided at the lower end of the leg;

Figure 9 is a view showing the connection 85 between the outer end of the corner arm and the leg for supporting the latter;

Figure 10 is a plan view of Figure 9; and

Figure 11 is a perspective view showing the device used as a workman's support upon a roof, when shingling or surfacing the latter.

In the selected embodiment of the invention here shown, there is illustrated in Figure 1, a sectional plan view of a corner of a building, comprising the walls 2 and 3 supported by suitable uprights or studdings 4.

Two different sizes of scaffold supports are preferably used in the erection of a scaffold, as shown in Figure 1. The supports used on the sides of the building each comprise an arm 5, having an elongated opening or slot 6 provided at the outer end thereof adapted to receive a tongue 7, terminally pro-

vided upon a leg 8. The opposite end of the leg 8 has a tooth or prong 9 adapted to pierce the surface of the wall or studding to secure the lower end of the brace thereto. The leg 5 is preferably of angle iron cross-section, and one flange thereof is cut away at the lower end of the leg to form the tooth 9 and to provide an offset extension 11, adapted to engage the surface of the wall, as indicated in Figure 10 7. A slot 12, preferably diamond-shaped, is provided in the extension 11 to receive a nail 13 for securing the lower end of the leg 8 to the wall, to prevent it from accidentally becoming disengaged therefrom. (See Figure 15 7.)

The means provided for detachably securing the arm to the surface of the wall or studding is shown in Figure 4, and consists of a bracket 14 which is suitably secured to a hook 20 15, terminally formed on the arm 5 as shown. Diamond-shaped slots 16 are provided in the bracket 14 adapted to receive nails or similar devices for securing the bracket to the wall. The provision of the diamond-shaped slots 25 16 is an important feature of this invention, in that they provide means whereby the bracket may be quickly removed from the wall without the necessity of having to remove or withdraw any nails from the wall. 30 The central enlarged portion of each slot is of sufficient size to permit the head of the nail to pass therethrough, while the upper ends of the slots function to prevent the heads of the nails from passing through the slots, 35 when the arm 5 is secured to a wall, as shown in Figure 2. A similar shaped slot 17 is provided at the outer end of the arm 5 as shown in Figure 5.

A brace member 18 has one end pivotally connected to the arm 5 intermediately thereof. The opposite end 19 of the brace member is off-set and apertured to receive a nail 21 for securing that end of the member 18 to the wall. This brace member functions 45 to prevent the arm and leg from swaying, when in operative position, as shown in Figures 1 and 2.

In order to provide a suitable support for the boards or planks 22, indicated in dotted lines in Figure 1, the arm 23 of the corner support is preferably longer than the arm 5, previously described. The necessity of this will readily be understood by reference to Figure 1. Each arm 23 is likewise provided 50 at its inner end with a hook member 24, having an angled bracket 25 secured thereto, the ends of which are provided with diamond-shaped slots 26, as shown in Figure 3. These slots are arranged transversely of the ends of 55 the bracket 25 so that the restricted or reduced end portions thereof will be substantially vertically aligned. When nails are inserted in the slots and driven into the surface of the building wall, the bracket 25 will 60 be prevented from accidentally becoming de-

tached from the wall as a result of the nail-heads being too large to pass through the reduced ends of the slots. To remove the bracket from the nails, it is only necessary to lift the bracket upwardly a distance sufficient 70 to allow the heads of the nails to pass through the enlarged central portions of the slots. To remove the corner bracket 25 from the corner of a building, when positioned thereon, as shown in Figure 1, it may be necessary to 75 slightly bend the nails before the brackets can be disconnected therefrom, as a result of the nails being driven in at right angles to each other. This, however, is not always necessary. 80

The outer end of each arm 23 is provided with an up-turned lug 27 which functions as a guide or stop to prevent the outer planks or boards from slipping off the support. A leg 28 having an off-set lug 29 terminally provided thereon, provides means for bracing the arm 23. The lug 29 is adapted to be received in a slot 31 provided in the vertical flange 32 of the arm 23. The lug 29 is suitably apertured to receive a nail 33 or other 90 suitable device to prevent the arm from accidentally becoming disengaged from the upper end of the leg 28, when the arm and leg are connected together as shown in Figures 3, 9, and 10. The lower end of the leg 28 is also provided with a tooth or prong 34, adapted to engage the side wall or studding. An off-set extension 35 is also provided at the lower end of the leg 28, having an aperture therein adapted to receive a 100 nail 36 for securing the latter to the wall. 95

From the foregoing, it will readily be seen that this novel scaffold support is well adapted for use to support scaffolds such as are commonly employed in the construction of 105 buildings. By means of the diamond-shaped slots 16, which, by the way, function in a manner similar to an ordinary key slot, the arms 5 and 23 may be quickly removed or detached from the wall, when it is desired 110 to take down the scaffolding. As before stated, the slots 16 permit the arms to be removed from the wall without the necessity of removing the nails therefrom. After the arms have thus been detached from the nails, 115 the latter may be driven into the wall.

An important feature of the structure also resides in the invertibility of the arm 5. This has been found of particular advantage when, for instance, the arm is secured to the 120 wall adjacent to a window or door opening, as shown in the upper portion of Figure 2. When thus positioned and the arm is in an upright position as shown in Figures 2 and 4, should the inner end 19 of the brace member 18 happen to fall in the window or door opening, then the arm 5 may be inverted, as shown in Figure 1, thereby causing the brace member 18 to assume a position on the opposite side of the arm. The arm 5 may be 125 130

secured to the wall by means of the diamond-shaped slots 16 being engaged with nails driven into the wall as shown in Figure 2.

The supporting arms 5 are also adapted 5 for use to support the usual two-by-four or foot rest 37, used when shingling or re-surfacing a roof, as shown in Figure 11. When thus used, the brace member 18 is folded against the arm 5 and the two-by-four 37 is 10 engaged with the hook 15 provided at one end of the arm. The opposite end of the arm is detachably secured to the roofing boards 38 by means of a nail 39 inserted in the key slot 17, shown in Figure 5. The key 15 slot 17 permits the arm 5 to be detached from the nail 39 by simply moving the arm upwardly sufficiently to permit the nail head to pass through the enlarged central portion of the slot.

20 I claim as my invention:

1. A scaffold support comprising a flanged arm having a bracket secured to one end thereof provided with means for detachably securing it to a wall, an elongated opening 25 in a flange of said arm adjacent its opposite end, a leg having a tongue at one end adapted to be received in said elongated opening, and means at the opposite end of said leg adapted to engage and dig into the surface of the 30 wall to provide a support for said arm.

2. A scaffold support comprising a flanged arm having a bracket secured to one end thereof provided with means for detachably securing it to a wall, an elongated opening 35 in a flange of said arm adjacent its opposite end, a leg having a tongue adapted to be received in said elongated opening, a tooth at the opposite end of said leg adapted to engage the wall to retain the leg in operative 40 position, and a brace member pivotally connected with said arm and having one end adapted to be secured to the wall to prevent swaying of the scaffold support.

3. A scaffold support comprising an arm 45 having an elongated opening at one end thereof and a hook formed at its opposite end, a leg having a terminal tongue adapted to be received in said opening to lock the arm and leg together, a tooth at the opposite end of 50 said leg adapted to engage a wall or upright, a bracket secured to the hooked end of said arm and having a plurality of slots therein adapted to receive nails or similar devices for securing the bracket and arm to the wall, 55 said slots being diamond-shaped and adapted to receive the heads of the nails, whereby the bracket may be disengaged from the wall without removing the nails therefrom.

4. A scaffold support comprising an arm 60 having a hook member formed at one end thereof, a leg having means for detachably connecting one end thereof to the arm and having a tooth or prong at its opposite end adapted to engage a wall, a bracket secured 65 to said hook member, having oppositely ex-

tending end portions, each provided with a plurality of diamond-shaped slots adapted to receive nails or similar devices for securing the arm to the wall or upright.

5. A scaffold support comprising an angle-iron arm having a horizontal and a vertical flange, an elongated opening at one end of the arm, a brace member having one end pivotally connected to the horizontal flange of said arm and having its other end adapted 70 to be secured to a wall to brace the arm horizontally, a leg having a tongue adapted to be received in the opening in said arm, a tooth at the opposite end of said leg adapted to engage a wall or upright, a bracket secured 75 to the opposite end of said arm and having a plurality of vertically disposed diamond-shaped slots therein adapted to receive nails or similar devices for detachably securing the bracket and arm to the wall, the reduced end 80 portions of each slot being adapted to receive the body of the nail and to prevent the head from passing therethrough, and the enlarged central portion of each slot permitting the nail heads to pass therethrough, whereby the 85 bracket may be disengaged from the wall without removing the nails therefrom, and the connection between said arm and said leg and the particular shape of said slots permitting the arm to be inverted.

6. A scaffold support comprising a supporting member having a horizontal flange and a vertical flange, a slot in the horizontal flange adjacent one end thereof, a terminal hook formed in the vertical flange of the 90 member at the opposite end thereof, an elongated bracket secured to said hook and having elongated apertures adapted to receive nails for securing the bracket and arm to a wall or upright, a diagonal brace of angle-iron cross-section having one flange provided 95 with an inclined terminal tongue adapted to be received in said slot and to detachably secure together said supporting member and brace, a tooth at the opposite end of said 100 brace flange adapted to engage the wall or upright, and the other flange of said brace having a terminal off-set portion adjacent to said tooth also adapted to engage the wall or upright, and an elongated aperture in said 105 off-set portion adapted to receive a nail for securing the lower end of the brace to the wall.

7. A scaffold support comprising a supporting member of angle-iron cross-section and the flanges of which are substantially 110 horizontally and vertically disposed, when the scaffold is set up, a slot in the horizontal flange of said member adjacent one end thereof, a terminal hook formed in the vertical flange of the member at the opposite end thereof, an elongated bracket secured to said 115 hook member, alined diamond-shaped slots in said bracket adapted to receive nails for securing the bracket and arm to a wall or upright, a diagonal brace of angle-iron cross- 120

section having an inclined terminal tongue adapted to be received in said slot and to detachably secure together said supporting member and brace, a tooth at the opposite end of said brace adapted to engage and pierce the surface of the wall or upright to support the lower end of the brace, an inclined strap-like portion integrally formed with the lower

end of the brace adjacent to said tooth, also adapted to engage the surface of the wall, and a diamond-shaped aperture therein adapted to receive a nail for positively securing the brace to the wall or upright. ¹⁰

In witness whereof, I have hereunto set my hand this 22nd day of October, 1927.

GEORGE E. SLOAN
